UNITED STATES PATENT OFFICE.

JOHN COLLIS, OF DES MOINES, IOWA.

STEAM-RADIATOR.

SPECIFICATION forming part of Letters Patent No. 290,665, dated December 25, 1883.

Application filed March 29, 1883. (No model.)

To all whom it may concern:

Be it known that I, JOHN COLLIS, a citizen of the United States of America, residing at Des Moines, in the county of Polk, State of 5 Iowa, have invented certain new and useful Improvements in Steam-Radiators, of which the following is a specification, to wit:

This invention relates to steam-radiators; and it consists in providing the upright pipes 10 of a radiator with a small diaphragm or partition near their upper ends, whereby each pipe is divided into two parts and the steam caused to circulate, substantially as will be hereinafter more fully set forth.

15 In order to enable others skilled in the art to which my invention appertains to make and use the same, I will now proceed to describe its construction and operation, referring to the accompanying drawings, in which— 20 Figure 1 is a central vertical section of part of a radiator, and Fig. 2 is a cross-section through two of the pipes.

A represents the base of a steam-radiator, from which rise any desired number of pipes, 25 B, screwed into the base. The pipes are closed at their upper ends by screw-caps C, each of which is provided with a central partition or diaphragm, arranged vertically, as seen at c, and having a space between their 30 upper edges and the top of the cap. The caps are formed with an extension, b, on top, adapted to be clutched by any device for securing them on, and also for screwing the pipes into the base, which enables me to place the radiator-pipes much nearer together than by the 35 old method, and also to use machinery for putting the whole together, while in ordinary cases this must be done by hand, and space

left between the pipes for the use of the usual tongs. The steam from the base A passes into 40 each pipe B, and the partition at its upper ends causes a division and circulation of the steam up one side of the pipe and down the other, passing over the partition.

I have represented in one of the pipes a 45 small tube passing vertically through the diaphragm, which will in some cases be found desirable.

Any repairs which may become necessary in a radiator made in this way are easily and 50 quickly made by the removal of one or more pipes or their caps.

Having thus fully described my invention, what I claim as new, and desire to secure by Letters Patent, is—

1. A radiator tube or pipe provided with a 55 small vertical partition near its outer end, having a space between the partition and the end of the pipe, substantially as and for the purpose set forth.

2. In a radiator, the pipes B B, each having a removable cap or extension, provided with a vertical partition, having a space between it and the upper end of the cap, substantially as and for the purpose set forth.

3. A steam-radiator pipe having its diaphragm suspended from a removable cap upon the outer end of the pipe, whereby repairs are facilitated, substantially as shown and described.

In testimony whereof I affix my signature in the presence of two witnesses.

JOHN COLLIS.
